PASTE-APPLYING MECHANISM FOR BAG MACHINES

George W. Poppe, Brooklyn, N. Y., assignor to
Equitable Paper Bag Co., Inc., Brooklyn, N. Y.
a corporation of New York

Original application September 30, 1932, Serial
No. 635,533. Divided and this application June
21, 1933, Serial No. 676,874.

2 Claims. (Cl. 93—18)

This invention relates to a machine for making bags and more particularly to the making of bags of relatively thin material. The improvements, however, are not limited to a machine for handling thin material but possess advantages for making bags of ordinary paper.

This application is a division of my application Serial No. 635,533, filed September 30, 1932.

An object of the present invention is a better control of the application of the paste to the paper web prior to folding the same into a bag tube.

A feature of the invention relates to the construction and mode of operation of the paste applying disk whereby the paste is more evenly applied.

A further feature of the invention relates to the manner of rotating the paste applying disk and to the manner of adjusting the same.

Other features and advantages will become apparent from the following description and claims when taken in connection with the following drawings in which—

Figure 1 is a longitudinal section of a bag machine embodying my improvements;

Figure 2 is a plan and part sectional view on line 2—2, Figure 1;

Figure 3 is a part sectional and part plan view of a portion of the rear of the machine substantially along the line 3—3, Figure 1;

Figure 4 is a detail of the shaft carrying the paste applying disk;

Figure 5 is a detail of a modified form of the paste-applying disk;

Figure 6 is a section on the line 6—6, Figure 5; and

Figure 7 is a section on the line 7—7, Figure 3.

Referring to the drawings and more particularly to Figures 1 and 2 there is the usual supporting framework 2, the side members of which carry the various shafts for driving the usual mechanism of a bag machine, together with brackets for supporting the various auxiliary structures with which the present invention is more particularly concerned.

Referring to Figure 2, the machine is driven from a motor 4 whose shaft is provided with a pulley 5 about which passes a belt 6 to a pulley 7 on the shaft 8, which carries the lower pinch roller and from which shaft most of the other parts receive their drive. On this shaft is also carried a sprocket wheel over which passes a sprocket chain 10 connected to a sprocket 11 on shaft 12, Figures 2 and 3. A tension roller 13 is provided to keep the sprocket chain sufficiently

taut. The shaft 12 carries a gear that meshes with a similar gear on stud shaft 14. The latter shaft carries a sprocket wheel for engagement with a sprocket chain 15 by which motion is transmitted to shaft 16.

The paper or other material which is to form the bags is fed as a web 18 from a roll 19 supported on a shaft 20 in the lower portion of the rear framework. The web passes over guide rollers 22, 23 and 24 and around another roller 26 which reverses its direction of movement, the latter roller being carried by shaft 27.

The mechanism so far described is that which is found in an ordinary bag machine and is of well-known construction. In such machines, however, the roller 26 serves merely to reverse the direction of the web but is not itself positively driven. In the drawings illustrating the present improvements I have shown a construction wherein the roller 26 is positively driven in timed relation with the feed rollers but this subject matter is not described in detail nor claimed herein but is described and claimed in my divisional application Serial No. 676,871 filed June 21, 1933, which is also a division of my application Serial No. 635,533 above referred to. Insofar as the present invention is concerned, however, the roller 26 may or may not be positively driven.

The paper web after passing over the roller 26 is delivered to mechanism which folds it into the bag tube in the usual manner, such mechanism including a former plate 38, the right end of which, as indicated in Figure 1, is bent upwardly at about 45°. The former is supported from a bridge 40 carried by arms 41 projecting forwardly and upwardly. The web passes under the former and is folded over on to it as illustrated in Figure 2. Projecting upwardly from the side plates 2 are four standards 42 which support two plates 43, Figure 2, the plates being separated sufficiently to permit the bag tube to freely move between them. Adjustment of the plates to and from each other is effected by slotting the plates as shown in Figure 2 and providing set screws to hold them in the proper adjustment. These plates 43 support rollers which aid in giving the necessary control of the folded web.

The folded tube passes to the feed rollers indicated at 44, the upper pair of which are mounted on shaft 45 and the lower pair on shaft 46, these shafts extending into and being supported by the side frames of the machine. Preferably the upper rollers are provided with facings 44a of

rubber, leather or other material such as will provide the desired surface friction. The lower rollers are of steel without facings. For driving the feed rollers there is provided a gear 48 on the shaft 8, Figures 2 and 3, which gear meshes with an idler 50 which in turn meshes with a gear 51 on the lower shaft 46. Near its other end but within the frame 2 the shaft 46 carries gear 52 meshing with gear 53 on the upper shaft 5 10 45. The gears 52 and 53 are of the same size so that the feed rollers rotate in a 1 to 1 ratio.

After the web has been formed into a bag tube by being folded over the former and passes between the feed rollers 44 it is severed into a bag 15 length by mechanism including the so-called pinch bars and the striker bar. The pinch bars are also driven from the shaft 8 which has secured to it a pinion 55 meshing with a pinion 56 on the upper shaft 54 which carries the pinch 20 25 bar 47, the pinions 55 and 56 also driving in a 1 to 1 ratio.

After the severance of the bag tube it passes on to mechanism which closes the bag bottom and this mechanism is of the usual and well-known construction and consists of upper and lower cylinders carrying respectively a tucker blade and clamp, which cylinders are likewise driven from the shaft 8.

The particular improvements described and 30 claimed in the present application relate to the mechanism for applying paste to the web before it is folded into a tube.

I have found as a matter of practical experience that there is difficulty in uniformly applying 35 paste by the ordinary paste-applying roller when the web is of very thin material. Heretofore the paste-applying cylinder or disc has been supported for free rotation adjacent the roller 26 and was so positioned as to bear upon the paper 40 in contact with the roller. I have found in actual practice that when such a paste applying mechanism is used the pressure of the paste-applying disc against the roller has resulted in a flattening 45 of the edge of the disc leading to undesirable results.

I have therefore overcome these difficulties by mounting the paste-applying roller somewhat lower down and arranging it so that it lightly presses against the paper web before the web 50 encounters the roller 26. I also arrange to positively drive the disc in the same direction as the paper web is moving. The mechanism for this purpose consists in the following:

Referring to Figure 1, I provide a pulley 130 55 on shaft 46 about which passes a belt 132 which belt passes about a second pulley 134 carried by the shaft 135 which is connected to drive the paste-applying disc 136, Figure 3. The belt is held taut by an adjustable roller 137. Since 60 the pulley 130 rotates in an anti-clockwise direction and it is desired to drive the shaft 135 in a clockwise direction the belt 132 is crossed as clearly indicated in Figure 1. The disc 136 dips into a paste-pot 138 having legs 139 extending downwardly on either side of the machine, said legs pivotally engaging a rod 140 supported 65 in arms 141 extending rearwardly from the side

frames of the machine. An adjusting screw 142 bears against the underside of the paste-pot for giving to the disc the proper degree of pressure against the paper web. The paste applying disc 136 is secured to a shaft 144 which shaft for the purpose of enabling it to be easily inserted into and removed from its bearings is made as shown in Figure 4. As there shown the shaft has flattened portions 146 which fit into elongated openings in the bearings 147 and after the shaft has 10 been set into the openings it is moved lengthwise and a clamping collar 148 having a clamping screw 149 secures the shaft in the position to which it has been adjusted as will be readily understood from Figures 3 and 4. In Figure 3 15 the shaft 144 is shown as occupying normal position, which is 90° from that shown in Figure 4, to more clearly indicate the nature of the flat portions 146. The upper flat portion Figure 3 is of course under the collar 148 and is therefore 20 indicated by dotted lines. The upper end of the shaft as shown in Figures 3 and 4 carries a pin 150 which is eccentrically placed and engages one of two pins 151 projecting from a collar 152 on the shaft 135. By reason of this coupling between the shafts 135 and 144 the latter shaft may 25 be readily removed.

It is customary to have a scraping device which removes excess paste from the disc as its edge emerges from the paste. Such a scraper is 30 shown in Figure 3 and consists of a piece of flat metal 154 suitably slotted and a screw 155 provides for the necessary adjustment.

In Figures 5 and 6 I have shown a slightly modified construction for mounting the shaft 35 144. In this form of device in order to remove the shaft it is only necessary to turn the spring pressed clips 156 and lift the shaft out of its bearings.

When first threading the web into the machine 40 it is desirable that it does not come in contact with the paste disc and to prevent this I provide a forked device indicated at 158, Figure 3, which engages the web as shown in Figure 1 and which device may be rotated about its pivot 159 45 45 to hold the web free of the paste disc, the spring 160, Figure 3, supplying sufficient tension to frictionally hold the forks in position to which they are positively moved.

What I claim is:—

1. In a bag machine the combination with bag tube forming mechanism and means for feeding a web of paper to said mechanism, of a paste-applying disc, a shaft upon which said disc is mounted, a second shaft, means for driving the 55 same and a separable connection between said disc shaft and said second shaft.

2. In a bag machine the combination with bag tube forming mechanism and means for feeding a web of paper to said mechanism including 60 upper and lower feed rollers and supporting shafts therefor, of a paste-applying disc, a shaft therefor, a second shaft, means for driving the same from one of said feed roller shafts and a separable connection between the paste disc 65 shaft and said second shaft.

GEORGE W. POPPE.
